BURNER CONTROL APPARATUS

Lewis L. Cunningham, Glendale, Calif., assignor
to Perfex Corporation, Milwaukee, Wis., a cor-
poration of Wisconsin

Application June 20, 1941, Serial No. 398,923

23 Claims. (Cl. 158—28)

1

This invention relates in general to control apparatus, and more particularly to automatic controls for burners.

The primary object of this invention is the provision of a safety control device for a burner which functions to place the burner out of operation in the event of flame failure or extinguishment of the fire, and which is simple and inexpensive in construction and reliable in operation.

Other objects of the invention will become apparent from the following description and the appended claims.

For a full disclosure of the present invention reference is made to the following detailed description and to the accompanying drawing, in which

Fig. 1 illustrates schematically one form which the invention may take;

Fig. 2 shows a portion of the apparatus of Fig. 1 in the position it assumes while the burner is operating properly; and

Fig. 3 is a view similar to Fig. 2 but showing the parts in the positions they assume when the burner is stopped due to flame failure.

Referring primarily to Fig. 1, reference character 1 indicates an electric motor for operating a burner which may be an oil burner or a stoker. The burner might also be a gas burner, and in such case the motor 1 would operate the gas valve therefor. Reference character 2 indicates an electrical igniter for the burner which may be of any satisfactory form. The motor 1 and the igniter 2 are controlled by means of a relay generally indicated as 3. This relay is illustrated diagrammatically as comprising a coil 4 which operates switch arms 5, 6 and 7 through a suitable armature, not shown. When the relay coil 4 is energized the switch arms 5, 6 and 7 engage contacts 8, 9 and 10 respectively. When coil 4 is deenergized the switch arms are disengaged from their respective contacts as shown.

The igniter 2 and the relay 3 are controlled by means of a timing device or switching mechanism generally indicated as 11. This device is diagrammatically illustrated as comprising a bimetal element 12 which is fixedly secured to a block 13 at one end and which carries an armature 14 at its other end, this armature cooperating with a permanent magnet 15. The bimetal element 12 is preferably compensated for changes in ambient temperature by well known means (not shown) and actuates a pair of movable contacts 16 and 17 which cooperate with fixed contacts 18 and 19 respectively. The movable contacts 16 and 17 may be of any desired construction and

2

are diagrammatically shown as attached to a spring member 20 which is riveted at its midpoint to the bimetal element 12, the contacts 16 and 17 extending through suitable apertures in element 12. Contacts 17 and 19 cooperate to form an igniter switch for controlling the igniter 2. Contacts 16 and 18 cooperate to form a starting switch for the relay 3. The bimetal element 12 is provided with a pair of electric heating elements 21 and 22. When the bimetal element 12 is relatively cold it assumes the position shown in which the movable contacts 16 and 17 engage the fixed contacts 18 and 19, the armature 14 being attracted by the permanent magnet 15 but being spaced therefrom by engagement of the movable contacts with the fixed contacts. However, when the bimetal element 12 is heated under the action of heaters 21 or 22, this element tends to bow upwardly, being initially restrained from such movement by the attraction of armature 14 to magnet 15. When element 12 is heated sufficiently to overcome the magnetic attraction it snaps upwardly, causing the movable contacts to disengage the fixed contacts. When the element 12 cools down due to the heaters 21 and 22 being deenergized, this element bows downwardly and the movable contacts engage the fixed contacts with snap action.

The relay 3, in addition to the switch arms 5, 6 and 7, also includes a pivoted movable member 24, having an armature portion 25 which is adapted to cooperate with the open end of the U-shaped permanent magnet 15 when the relay is deenergized. This provides a magnetic shunt and thus decreases the effect of the permanent magnet 15 on the armature 14. The armature 25, movable with the relay, also serves to increase the voltage across relay 4 necessary to cause the relay to pull in. The relay also includes a mechanical stop member 26, which for illustrative purposes is shown as attached to the pivoted member 24. This stop member 26 includes an end portion 27 which is located in the path of movement of the movable member or bimetal element 12 whenever the relay 3 is deenergized. When the relay 3 is energized, the stop means 27 is withdrawn from the path of movement of the free end of bimetal element 12, as shown in Fig. 2.

The control system also includes a combustion responsive device generally indicated as 30. This device may include an expansible element 31 which is fixed at one end and which extends into the stack or combustion chamber of the furnace, the free end of this member being attached to

a non-expanding rod 32 which operates through a slip friction mechanism 33 to rock an operating beam 34 about a fixed pivot 35 and between adjustable stops 36 and 37. This operating beam positions a combustion stop means 38 which is shown in the form of a movable abutment. When no combustion is present, the thermal element 31 is cool, which causes the operating beam 34 to be urged against the cold stop 36. This causes the abutment 38 to be clear of the path of movement of the free end of bimetal element 12 as shown. When combustion takes place the thermal element 31 becomes heated, expanding and acting through the slip friction device 33 to rock the operating beam 34 counter clockwise, thus bringing the abutment 38 into the path of movement of bimetal element 12 as shown in Fig. 2. The combustion responsive means 30 also serves to position the movable relay contact 8 which cooperates with the relay switch arm 5. This is illustrated diagrammatically as accomplished by an insulating member 39 secured to the operating beam 34, this insulating member carrying a stiff contact arm 40 and an adjusting screw 41. The movable contact 8 may be carried by a resilient arm 42 attached to arm 40. The operating mechanism for the movable relay contact 8 is proportioned so that this contact will remain disengaged from the switch arm 5 whenever the operating beam 34 is in its cold position as shown. Also the range of movement of the movable contact 8 preferably should not substantially overlap with that of the switch arm 5, so that when the switch arm 5 is in the position shown due to the relay being deenergized it will not be engaged by the movable contact 8, regardless of whether combustion is present or not. The combustion responsive device 30 also may operate a second switch for controlling the heater 22 of the timing device 11. This switch is diagrammatically shown as comprising a switch arm 43 which is carried by an insulating member 44 attached to operating beam 34, this switch arm co-operating with a stationary contact 45. The movable contact 43 should engage the stationary contact 45 only when combustion is present.

In addition to the control instrumentalities above described, the system also includes a condition responsive device 48 which may be a room thermostat or other device for starting the burner upon demand for heat and for stopping the same when the demand for heat is satisfied. The control system also includes a transformer 49 having a primary coil 50 and a secondary coil 51. Preferably the system also includes a limit or safety control 52 which may be a thermostat or pressure responsive device on the furnace for placing the burner out of operation in case of excessive furnace temperatures or pressures.

Operation

With the parts in the positions shown, the room thermostat 48 is satisfied, which causes the relay coil 4 to be deenergized. The motor and igniter for the burner at this time are deenergized. Also the bimetal element 12 is cold, causing the movable contacts 16 and 17 to engage the fixed contacts 18 and 19. As the burner is not in operation the operating beam 34 of the combustion responsive device is in its cold position, in which the abutment 38 is clear of the path of movement of the bimetal element 12. The movable contact 43 at this time is disengaged from the fixed contact 45 and the movable contact 3 is positioned so that it cannot be en-

gaged by the switch arm 5 of the relay, even if the relay were energized. At this time a potential starting circuit for the relay 3 is provided as follows: from line wire 53, limit control 52, line wire 54, wire 55, wire 56, bimetal element 12, movable contact 16, stationary contact 18, wire 57, relay coil 4, wire 58 and transformer primary coil 50 to line wire 59. As the room thermostat 48 is satisfied it opens the circuit through secondary coil 51 and the transformer primary coil 50 therefore acts as a choke, which prevents substantial flow of current through the relay coil 4. The relay 3 is thus deenergized even though the potential starting circuit through contacts 16 and 18 is completed.

When the room thermostat calls for heat it closes a circuit between the transformer secondary 51 and electric heater 21 as follows: from secondary 51, wire 60, thermostat 48, wire 61, heater 21 and wire 62 to secondary 51. This causes current to flow through the electric heater 21 for heating bimetal element 12 and simultaneously reduces the choke action of the transformer 49 sufficiently to permit the relay 3 to pull in to running position. Thus switch arms 6 and 7 are brought into engagement with contacts 9 and 10. However, the switch arm 5 does not at this time engage the contacts 8 due to the combustion responsive device still being in its cold position. Engagement of switch arm 7 with contact 10 energizes the burner motor 1. Engagement of switch arm 6 with contact 9 establishes an energizing circuit for the igniter 2 as follows: line wire 54, wire 55, wire 56, bimetal element 12, movable contact 17, stationary contact 19, wire 64, contact 9, switch arm 6, wire 65 and igniter 2 to line wire 59. Thus when the thermostat calls for heat the relay 3 is energized, the burner motor being placed into operation directly and the igniter being energized through the igniter contacts 17 and 19 of the timing device 11. Also the electric heater 21 of the timing device is energized simultaneously with starting of the burner. At this time the relay stop member 27 is withdrawn from the path of movement of the bimetal element 12 as shown in Fig. 2.

Occurrence of proper combustion

If combustion occurs properly the operating beam 34 will be moved against its "hot" stop 37 wherein the abutment 38 is in the path of movement of the free end of bimetal element 12. This same movement of the operating beam 34 will also shift the movable relay contact 8 into engagement with the switch arm 5. Engagement of contact 8 with switch arm 5 will establish a new energizing circuit for the relay coil which is independent of the starting switch 16-18. This holding or running circuit is as follows: from line 60 wire 54, wire 66, flexible arm 42, movable contact 8, switch arm 5, wire 67, wire 57, relay coil 4, wire 58 and transformer primary 50 to line wire 59. In response to combustion the combustion responsive device in addition to moving the abutment 38 into active position and establishing a holding or running circuit for the relay, also causes switch arm 43 to engage contact 45 which energizes the heater 22 of the timing device 11. This circuit may be traced as follows: from line 70 wire 54, wire 55, wire 56, bimetal element 12, movable contact 17, stationary contact 19, wire 64, wire 68, heater 22, wire 69, movable contact 43, fixed contact 45, wire 70, ballast resistor 71, and wire 72 to line wire 59. The heater 21 when energized alone would cause the movable contacts

to snap away from the fixed contacts in a predetermined period of time, such as 90 seconds after starting of the burner. The purpose of the heater 22 and the combustion contacts 43—45 is to shorten this period when the burner operates properly. When combustion occurs the operation of the igniter is unnecessary and it is desirable to place it out of operation a short time thereafter. Due to the heater 22 supplementing the action of heater 21, the bimetal element 12 is heated in a short time sufficiently to overcome the attraction of armature 14 to magnet 15. The bimetal element then snaps upwardly against the abutment 38 as shown in Fig. 2, in which position the movable contacts 16 and 17 are disengaged from contacts 18 and 19. Disengagement of contact 17 from contact 19 breaks the energizing circuit for the igniter 2 and also breaks the energizing circuit for the heater 22. The igniter is therefore placed out of operation and the heater 22 is deenergized, the bimetal element 12 being retained in its hot position solely by the influence of heater 21. Disengagement of contact 16 from contact 18 breaks the starting circuit for the relay. The relay, however, is maintained energized through the holding or running circuit extending through combustion contact 8 and switch arm 5 of the relay. When the room thermostat becomes satisfied it opens its circuit, thus deenergizing heater 21 and once more causing the transformer 49 to function as a choke for deenergizing the relay coil 4. The relay switch arms 5, 6 and 7 therefore disengage their respective contacts and the burner stops. Due to the switch arm 5 now being disengaged from the contact 8 the relay cannot be energized once more until the bimetal element 12 cools down for reengaging contacts 16 and 17 with contacts 18 and 19. As a result the burner can never be started unless the ignition controlling contacts 17 and 19 of the timing device 12 are in engagement.

Failure of flame on starting

If combustion does not take place after starting of the burner, the operating beam 34 of the combustion responsive device will remain in the position shown in which the abutment 38 is out of the path of bimetal element 12, the combustion contact 8 is out of reach of switch arm 5, and in which the switch 43—45 for the accelerating heater 22 is open. Under these conditions the burner will operate with the ignition on until the heater 21 heats the bimetal element 12 sufficiently to cause this element to overcome the attraction of magnet 15. This period is preferably approximately 90 seconds. At the end of this period the bimetal element 12 snaps upwardly. As the abutment 38 is not in its path, this element will snap upwardly to a position beyond the relay abutment member 27. At the same time the contact 16 is disengaged from contact 18 which breaks the starting circuit for relay coil 4. Due to the holding or running circuit for the relay coil never having been closed, the relay becomes deenergized at this time and moves to its "out" position for stopping the burner. The relay abutment 27 now becomes interposed between the free end of bimetal element 12 and the cold position thereof, as shown in Fig. 3, which prevents reengagement of the starting contacts 16—18 and also prevents engagement of the ignition contacts 17 and 19. Due to the maintaining of the starting contacts 16 and 18 open in this manner, the relay cannot be energized until the abutment

27 is withdrawn from the path of movement of bimetal 12. This may be done manually by any suitable manual reset means. Such means is indicated diagrammatically in Fig. 1 as comprising a plunger 75 which is urged inwardly by a spring 76, this plunger extending through the abutment member 26 and having an enlarged head 77. By pulling on a handle portion 78 the abutment 27 may be withdrawn from the path of movement of bimetal 12, thus resetting the instrument for further operation of the burner. It will be noted that as the transformer primary 50 is in series with the relay coil, the secondary 51 of the transformer becomes deenergized when the control assumes its lockout position of Fig. 3. Consequently the heater 21 is deenergized at this time and the bimetal element 12 becomes cold. Thus when the resetting member 78 is operated, the bimetal 12 snaps to its cold position for permitting immediate restarting of the burner.

Failure of flame while running

When the burner has been operating properly but then loses its flame, the operating beam 34 of the combustion responsive device 30 will be rocked clockwise from its "hot" stop 37 to its "cold" stop 36, thus moving the abutment 38 out of the path of bimetal element 12 and also shifting the combustion contact 8 out of reach of the switch arm 5.

The particular sequence of operation which occurs upon flame failure during operation of the burner depends upon the setting of the adjusting screw 41 which positions the contact 8 with respect to the abutment member 38. If non-recycling operation is desired, the adjusting screw 41 is adjusted so that the contact 8 remains in engagement with the switch arm 5 until the abutment member 38 is shifted clear of the bimetal element 12. The relay coil 4 will thus remain energized and the relay abutment will thus remain out of the path of bimetal 12 at the time that the combustion abutment 38 releases this element. The element 12 will therefore snap from the position of Fig. 2 to the position of Fig. 3. Upon further movement of the operating beam 34 the contact 8 will disengage from switch arm 5 which breaks the running circuit for the relay. The relay will therefore become deenergized, moving to its "out" position for stopping the burner and causing its abutment 38 to prevent return of the bimetal 12 to its cold position. The burner will therefore remain out of operation until the control is manually reset.

If it is desired that the control recycle after a flame failure during operation of the burner, instead of locking out immediately as above described, the adjusting screw 41 may be adjusted so that the movable contact 8 disengages the switch arm 5 before the abutment 38 is shifted out of the path of bimetal element 12. With this adjustment of screw 41, upon a flame failure the operating beam 34 will be rocked toward its "cold" stop 36. The first action of this movement will now be to disengage contact 8 from switch arm 5. This will break the running circuit for the relay coil 4 and consequently this coil will be deenergized and also the heater 21 will be deenergized. The relay will thus drop out and stop the burner and the bimetal element 12 will begin cooling. Due to the abutment 38 still being in engaging relationship with the bimetal element 12 when the relay drops out, the relay abutment 27 when it returns to the position shown in Fig. 1 will not prevent return movement of the bimetal 12 to its

cold position. When the bimetal element 12 cools sufficiently to cause reengagement of the movable contacts 18 and 19 with the fixed contacts 18 and 19, the burner will restart in the manner above described. If combustion now occurs before the bimetal element moves to its hot position, the control will operate in the manner described for retaining the burner in operation until the thermostat 48 becomes satisfied. If flame does not occur within the timing period of the timing device 11 the control will lock out in the manner described above and will retain the burner out of operation until the control is manually reset.

Power failure

In the event that the power should fail while the burner is running and after the ignition is cut off, the relay 3 will drop out and the heater 21 will become deenergized. When power is restored the burner will not start until the bimetal element cools down and returns to its cold position in which the starting switch and the timer ignition switch are closed. In the event that a power failure occurs just after the burner is started and before the bimetal 12 shifts to its hot position, the relay will drop out as above described. Due to the magnetic shunt 25 being shifted adjacent the permanent magnet 15 upon dropping out of the relay, the attraction of armature 14 to permanent magnet 15 will be considerably reduced. Consequently if bimetal element 12 is heated a substantial amount it will now snap to its "hot" position. The burner therefore cannot restart until the bimetal element 12 cools and returns to its cold position. This arrangement insures a full trial starting period when power is resumed.

From the foregoing description it will be apparent that the present invention provides a simple burner control system which provides for a safety shut down of the burner in the event of flame failure either upon starting of the burner or while the burner is running. It will also be apparent that the present invention controls the ignition for the burner and provides an entirely safe sequence of operation. While I have shown and described a preferred form of the invention, it is obvious that many changes may be made without departing from the spirit and scope of the invention. Also various parts may be omitted from the complete system without departing from the invention. For example, the ignition contacts 17 and 19 may be omitted where it is desired that the igniter operate continuously with the burner. Also the relay switch arm 5 could be omitted in certain applications of the invention. It is desired to be limited only by the scope of the appended claims.

What is claimed is:

1. In a burner control system, the combination of, control means responsive to the demand for heat for starting and stopping the burner, starting means movable from an inoperative position to a starting position, means normally preventing the burner from starting when the starting means is in said inoperative position and providing for starting of the burner when the starting means is in starting position, said starting means moving to inoperative position irrespective of combustion after starting of the burner, running means including combustion responsive means and a movable member operated thereby, said movable member being moved to running position only upon presence of combustion and serving to maintain the burner in operation independently of said starting means and under the control of said heat demand responsive means, said running means being incapable of initiating operation of the burner irrespective of said combustion responsive means, and means acting upon failure of combustion to prevent return of the starting means to starting position irrespective of said heat demand responsive means.

5. dependently of said starting means and under the control of said heat demand responsive means, and means responsive to failure of combustion for preventing return of the starting means to starting position irrespective of said heat demand responsive means.

2. In a burner control system, the combination of, control means responsive to the demand for heat for starting and stopping the burner, starting means movable from an inoperative position to a starting position, means normally preventing the burner from starting when the starting means is in said inoperative position and providing for starting of the burner when the starting means is in starting position, said starting means moving to inoperative position after starting of the burner, running means including combustion responsive means and a movable member operated thereby, said movable member being moved to running position only upon presence of combustion and serving to maintain the burner in operation independently of said starting means and under the control of said heat demand responsive means, means including mechanical holding means acting upon failure of combustion to prevent return movement of the starting means to starting position, and manual reset means for said holding means.

3. In a burner control system, the combination of, control means responsive to the demand for heat for starting and stopping the burner, starting means movable from an inoperative position to a starting position, means normally preventing the burner from starting when the starting means is in said inoperative position and providing for starting of the burner when the starting means is in starting position, said starting means moving to inoperative position irrespective of combustion after starting of the burner, running means including combustion responsive means and a movable member operated thereby, said movable member being moved to running position only upon presence of combustion and serving to maintain the burner in operation independently of said starting means and under the control of said heat demand responsive means, means including mechanical holding means acting upon failure of combustion to prevent return movement of the starting means to starting position, and manual reset means for said holding means.

4. In a burner control system, the combination of, control means responsive to the demand for heat for starting and stopping the burner, starting means movable from an inoperative position to a starting position, means normally preventing the burner from starting when the starting means is in said inoperative position and providing for starting of the burner when the starting means is in starting position, said starting means moving to inoperative position after starting of the burner, running means including combustion responsive means and a movable member operated thereby, said movable member being moved to running position only upon presence of combustion and serving to maintain the burner in operation independently of said starting means and under the control of said heat demand responsive means, said running means being incapable of initiating operation of the burner irrespective of said combustion responsive means, and means acting upon failure of combustion to prevent return of the starting means to starting position irrespective of said heat demand responsive means.

5. In a burner control system, the combination

of, control means responsive to the demand for heat for starting and stopping the burner, starting means movable from an inoperative position to a starting position, means normally preventing the burner from starting when the starting means is in said inoperative position and providing for starting of the burner when the starting means is in starting position, said starting means moving to inoperative position after starting of the burner, running means including combustion responsive means and a movable member operated thereby, said movable member being moved to running position only upon presence of combustion and serving to maintain the burner in operation independently of said starting means and under the control of said heat demand responsive means, said running means being incapable of initiating operation of the burner irrespective of said combustion responsive means, means including mechanical holding means and acting upon failure of combustion to prevent return movement of the starting means to starting position, and manual reset means for said holding means.

6. In a burner control system, the combination of, control means responsive to the demand for heat for starting and stopping the burner, starting means movable from an inoperative position to a starting position, means normally preventing the burner from starting when the starting means is in said inoperative position and providing for starting of the burner when the starting means is in starting position, said starting means moving to inoperative position irrespective of combustion after starting of the burner, running means including combustion responsive means and a movable member operated thereby, said movable member being moved to running position only upon presence of combustion and serving to maintain the burner in operation independently of said starting means and under the control of said heat demand responsive means, said running means being incapable of initiating operation of the burner irrespective of said combustion responsive means, and means acting upon failure of combustion to prevent return of the starting means to starting position irrespective of said heat demand responsive means.

7. In a burner control system, the combination of, control means for starting and stopping the burner including a starting circuit for the burner, starting switch means for said starting circuit, a running circuit for maintaining the burner in operation under the control of said control means independently of said starting circuit and being incapable of initially placing the burner into operation, first combustion responsive means for rendering the running circuit inoperative at all times when combustion is not present, and means including second combustion responsive means for controlling the starting switch means selectively to open the starting circuit and maintain the same open upon failure of combustion, or for opening the starting circuit and effecting reclosing of the same thereafter if combustion is proper.

8. In a burner control system, the combination of, control means for starting and stopping the burner, a starting switch arranged to prevent starting of the burner by said control means until the starting switch is in a starting position, running switch means arranged to maintain the burner in operation under the control of said control means independently of the starting switch means and being incapable of initiating operation of the burner, means including first combustion responsive means for rendering the running

switch means operative when combustion is present and inoperative at all times when combustion is not present, means actuated after starting of the burner for moving the starting switch from said starting position, and means including second combustion responsive means for controlling said starting switch selectively to effect return movement thereof to starting position after proper combustion or to maintain it away from starting position upon combustion failure.

9. In a burner control system, the combination of, a relay for starting and stopping the burner, condition responsive means responsive to the demand for heat in circuit with said relay, means including a starting switch for said relay and arranged to prevent starting of the burner until the starting switch is in starting position, holding switch means operated by said relay and adapted to maintain the burner in operation independently of said starting switch, said holding switch means being incapable of initiating operation of the burner, means including combustion responsive means for rendering said holding switch means operative when combustion is present and inoperative at all times when combustion is not present, means actuated after starting of the burner for moving said starting switch from said starting position, and means operative upon failure of combustion for preventing return movement of said starting switch to starting position irrespective of said condition responsive means.

10. In a burner control system, the combination of, a relay for starting and stopping the burner, control means for controlling said relay, starting switch means for controlling the relay and arranged to prevent starting of the burner until the starting switch means is in starting position, means including a running switch for controlling said relay and arranged to maintain the burner in operation under the control of said control means independently of said starting switch means, first means including combustion responsive means for actuating said running switch to maintain the burner in operation independently of said starting switch means only while proper combustion takes place, means actuated after starting of the burner for moving said starting switch means from starting position irrespective of combustion, and second means including combustion responsive means for selectively preventing return or effecting return of the starting switch means to starting position.

11. In a burner control system, the combination of, a relay controlling the burner and having a first position in which the burner operates and a second position in which the burner is normally out of operation, heat demand responsive means for controlling said relay and normally causing said relay to assume its first position upon demand for heat and to assume its second position when the demand for heat is satisfied, means including a starting switch for preventing movement of the relay from its second position to its first position unless the starting switch is in starting position, actuating means for the starting switch including a timing device for moving said starting switch from starting position a period of time after starting of the burner, means including combustion responsive means for maintaining the relay in its first position independently of said starting switch when combustion is present while causing movement thereof to its second position upon failure of combustion, and stop means controlled conjointly by the relay and combustion responsive means for prevent-

ing movement of the starting switch to starting position upon failure of combustion with the relay in its first position, while permitting return of the starting switch to starting position upon movement of the relay to its second position prior to termination of combustion.

12. In a burner control system, the combination of, a relay controlling the burner and having a first position in which the burner operates and a second position in which the burner is normally out of operation, heat demand responsive means for controlling said relay and normally causing said relay to assume its first position upon demand for heat and to assume its second position when the demand for heat is satisfied, means including a starting switch for preventing movement of the relay from its second position to its first position unless the starting switch is in starting position, actuating means for the starting switch including a timing device for moving said starting switch from starting position a period of time after starting of the burner, means including combustion responsive means for maintaining the relay in its first position independently of said starting switch when combustion is present while causing movement thereof to its second position upon failure of combustion, stop means actuated by movement of the relay to its second position for preventing movement of the starting switch to starting position, and combustion responsive means for preventing said stop means from being effective when the relay moves to its second position while combustion is present.

13. In a burner control system, the combination of, a relay controlling the burner and having a first position in which the burner operates and a second position in which the burner is normally out of operation, heat demand responsive means for controlling said relay and normally causing said relay to assume its first position upon demand for heat and to assume its second position when the demand for heat is satisfied, means including a starting switch for preventing movement of the relay from its second position to its first position unless the starting switch is in starting position, actuating means for the starting switch including a timing device for moving said starting switch from starting position a period of time after starting of the burner, a movable stop member adapted when in operative position to limit movement of the actuating means after movement of the starting switch from starting position, said movable stop member when in inoperative position permitting continued movement of the actuating means, means for moving said stop member to operative position when combustion is present and for moving said stop member to inoperative position when combustion is absent, means including combustion responsive means for maintaining the relay in its first position independently of said starting switch when combustion is present while causing movement thereof to its second position upon failure of combustion, and a second stop member operated by said relay upon movement to its second position and adapted to prevent return of the starting switch to starting position unless the movement of said actuating means is limited by said first stop member.

14. In a burner control system, the combination of, a relay controlling the burner and having a first position in which the burner operates and a second position in which the burner is normally out of operation, heat demand responsive means for controlling said relay and normally

causing said relay to assume its first position upon demand for heat and to assume its second position when the demand for heat is satisfied, means including a movable member and arranged to prevent the relay from moving from its second to its first position unless said movable member is in starting position, means for causing said movable member to move away from starting position a period of time after starting of the burner, means including combustion responsive means for maintaining the relay in its first position if combustion is present, and stop means controlled conjointly by the relay and combustion responsive means for preventing movement of said movable member to starting position upon failure of combustion with the relay in its first position, while permitting return of the movable member to starting position upon movement of the relay to its second position prior to termination of combustion.

15. In a burner control system, the combination of, a relay controlling the burner and having a first position in which the burner operates and a second position in which the burner is normally out of operation, heat demand responsive means for controlling said relay and normally causing said relay to assume its first position upon demand for heat and to assume its second position when the demand for heat is satisfied, means including a movable member arranged to prevent the burner from starting unless said movable member is in starting position, means for causing said movable member to move away from starting position a period of time after starting of the burner while permitting said burner to continue to operate, and means controlled by the relay and combustion responsive means for causing the movable member to remain away from starting position upon failure of combustion with the relay in its first position, while effecting return of the movable member to starting position after movement of the relay to its second position prior to termination of combustion.

16. In a burner control system, the combination of, a relay controlling the burner and having a first position in which the burner operates and a second position in which the burner is normally out of operation, heat demand responsive means for controlling said relay and normally causing said relay to assume its first position upon demand for heat and to assume its second position when the demand for heat is satisfied, means including a movable member arranged to prevent the burner from starting unless said movable member is in starting position, means for causing said movable member to move away from starting position a period of time after starting of the burner while permitting said burner to continue to operate, stop means actuated by movement of the relay to its second position for preventing movement of the movable member to starting position, and combustion responsive means for preventing said stop means from being effective when the relay moves to its second position while combustion is present.

17. In a burner control system, the combination of, a relay controlling the burner and having a first position in which the burner operates and a second position in which the burner is normally out of operation, heat demand responsive means for controlling said relay and normally causing said relay to assume its first position upon demand for heat and to assume its second position when the demand for heat is satisfied, means including relay actuated means actuated by

movement of the relay to its second position for preventing movement of the relay to its first position, and combustion responsive means for preventing said relay actuated means from being effective when the relay moves to its second position while combustion is present.

18. In a burner control system, a source of high voltage, a high voltage switch for selectively connecting or disconnecting the source of high voltage and the burner, means comprising a low voltage circuit and a room thermostatic switch connected therein for operating said high voltage switch, a movable member, means for normally causing said movable member to move from starting position to running position after the burner starts and to return to starting position after the burner stops, means comprising a second high voltage switch operated by said movable member for preventing the first high voltage switch from initially closing unless the movable member is in starting position, and means responsive to lack of combustion for opening said first high voltage switch and for preventing return of the movable member to starting position.

19. In a burner control system, means responsive to the demand for heat for stopping and starting the burner, means including first combustion responsive means for stopping the burner in case of flame failure during operation, said first combustion responsive means being incapable of preventing restarting of the burner, means including second combustion responsive means arranged to maintain the burner out of operation until manually reset, and means for relatively adjusting the combustion responsive means to selectively provide a recycling or non-recycling sequence of operation.

20. In a burner control system, the combination of, combustion responsive means for shutting down the burner in case of flame failure, automatic means for restarting the burner following a purging period after such flame failure shutdown, and adjustable means for selectively preventing or permitting restarting of the burner by said automatic means.

21. In a burner control system, the combination of, means including timing means and combustion responsive means for providing a trial operating period of the burner when first started, said means being constructed and arranged to permit continued operation if combustion is obtained but to stop the burner and prevent further operation until manually reset if combustion is not obtained, means for shutting down the burner on flame failure while the burner is in

30 35 40 45 50 55

operation, automatic means for restarting the burner following a purging period after such flame failure shutdown, and selective means for selectively preventing or permitting restarting of the burner by said automatic means.

22. In a burner control system, the combination of, a relay for controlling the burner, means including a movable member arranged to prevent initial energization of the relay unless the movable member is in starting position, means for causing said movable member to move from starting position toward a second position after energization of the relay, a first movable abutment operated by the relay and moved into the path of movement of the movable member when the relay is deenergized and out of the path of movement of said movable member when the relay is energized, said first abutment being adapted to prevent return of the movable member from its second position back to starting position, combustion responsive means, a second movable abutment operated by the combustion responsive means, said second abutment being moved out of the path of movement of the movable member when combustion is not present and being moved into the path of movement of the movable member when combustion is present, said second abutment in such position preventing the movable member from moving to said second position.

23. In a burner control system for a burner having a motor and igniter, the combination of, a relay for controlling the motor and igniter, a safety switch for controlling the relay, an ignition switch, timing means, means including a movable member operated by the timing means and having a starting position in which both of said switches are closed and a second position in which said switches are open, combustion responsive means acting upon presence of combustion to maintain the relay energized after said movable member moves from starting position, a first movable abutment operated by the relay and moved into the path of movement of the movable member when the relay is deenergized and moved out of said path when the relay is energized, a second movable abutment operated by the combustion responsive means, said second abutment being moved out of the path of movement of the movable member when combustion is not present and being moved into said path when combustion is present, said second abutment in the latter position preventing the movable member from moving to said second position.

LEWIS L. CUNNINGHAM.
